UNITED STATES PATENT OFFICE.

JAMES P. FISHER, OF BARTLESVILLE, OKLAHOMA, ASSIGNOR TO DOHERTY RESEARCH COMPANY, OF NEW YORK, N. Y., A CORPORATION OF DELAWARE.

BOILER GOVERNOR.

Application filed July 2, 1924. Serial No. 723,842.

The present invention relates to the automatic control of the steam pressure of boilers and is, more specifically an improvement on the construction disclosed in my 5 prior application for boiler governors filed Aug. 15, 1923, Ser. No. 657,505.

In the apparatus according to my said prior application, steam from a boiler to be controlled by the governor is passed through 10 an aspirator, to draw a current of air through a valve controlled passage. A dia- phragm subject to the steam pressure in said boiler operates the valve for controlling said passage to throttle the flow of air, 15 thus producing an increasing vacuum be- tween the valve and the aspirator with in- creasing boiler pressure. The fuel feeding means or damper operating means or both are governed by the vacuum so produced to 20 maintain a substantially constant boiler pressure.

In the practical operation of the said ap- 25 paratus, a difficulty has been encountered in maintaining a proper degree of regu- lation of the steam pressure in the boiler whenever the governor was fed with wet steam. The probable explanation of this difficulty is that the ordinary type of aspi- 30 rator illustrated in my said prior applica- tion, develops what is known as a "bushy" discharge when called upon to use steam con- 35 taining more than a small percentage of moisture and it is well known that an aspi- rator does not act efficiently and cannot 40 maintain a good vacuum when developing a "bushy" discharge. It has been necessary therefore to place the governor according to 45 my said prior application, near the steam dome of a boiler and thus in a place almost inaccessible to the fireman. The governor therefore would receive the minimum of attention and scale and dirt would often be permitted to collect in the steam passages and in the air passages until the apparatus 50 fails to maintain the desired steam pressure.

It is, accordingly, one of the objects of the present invention to produce a boiler governor having a simple and efficient aspirator structure capable of developing and 55 maintaining a good vacuum on wet steam.

A second object of the present invention is to provide a boiler governor having a high degree of sensitiveness.

A further object of the present invention 55 is to provide a boiler governor in which the

parts are readily accessible for inspection and in which a simple manipulation will enable the parts to clean themselves of any accumulated dirt or scale.

The present invention, together with fur- 60 ther objects and advantages, will be readily understood from the following description taken in connection with the accompanying drawing in which—

Fig. 1 is a plan of a boiler governor ac- 65 cording to the present invention;

Fig. 2 is a vertical section on the line 2—2 of Fig. 1;

Fig. 3 is a detail section taken on the 70 line 3—3 of Fig. 2; and

Fig. 4 is a detail section illustrating the 75 diaphragm and button construction of the governor illustrated in Figs. 1 and 2.

The boiler governor embodying the pres- 80 ent invention is constructed to develop a vacuum pressure by use of steam from the boiler, and this vacuum pressure is used to control the fuel feed and the air supply to the furnace. The vacuum pressure de- 85 veloped by the governor is automatically varied in accordance with the variations of the steam pressure to control the fire in the boiler furnace and thus maintain a constant boiler steam pressure.

An aspirator is used in the governor for 85 developing the vacuum pressure which is so constructed that it may operate effectively with wet steam and may be readily cleaned if the steam carries dirt or scale. The aspi- 90 rator is illustrated in Fig. 2 wherein 6 is a casing having therein a steam chamber 8 and a steam inlet 10 connected with said chamber, and designed to be connected to the interior of the boiler, the steam pressure of which it is intended to control. One wall 95 of chamber 8 has a threaded aperture 12 therein in which is supported an aspirator tube 14. The inner end of the tube 14 pro- 100 jects into the chamber 8, while the body of the tube extends through the threaded aper- 105 ture 12, an air chamber 16, and the outer wall of the casing 6. Two openings 18 are formed on the portion of the tube 14 which passes through the air chamber 16 to permit communication between the interior of the aspirator tube and the air chamber. A longitudinal bore extends through the tube 14 which consists of portions 20 and 22. The bore 20 extends from the inner end of the tube 14 to the openings 18 and the bore 110

22 extends from the openings 22 to the outer end of the tube 14. The diameter of the bore 20 is approximately one-half of the diameter of the bore 22, and is so designed to obtain the proper aspirating effect for maintaining the desired vacuum. A pin 24 extends the entire length of the bores 20 and 22 and has an enlarged tapering head 26 projecting into the steam chamber 8 with a portion of the head entering into the bore 20. The end of the pin 24 opposite the head 26 is reduced as shown at 28 and extends through a threaded plug 30 which closes the outer end of the bore 22. A socket 32 is formed in the outer end of the plug and reduced end 28 of the pin 24 extends into the socket at the time that a shoulder on the pin adjacent the reduced portion 28 is against the end of the plug. In the normal operation of the aspirator the pin 24 will be supported in the plug 30 with the head 26 resting on the lower portion of the bore 20. The steam pressure acting against the head 26 will tend to hold the shouldered end of the pin against the inner end of the plug 30. A lock nut 34 is threaded on the plug 30 by which it may be locked in any desired position when adjusting the plug to permit the desired amount of steam to pass between the head 26 and the bore 20. Opening 36 is formed in the outer end of the tube 34 just behind the plug 30 to permit the aspirating steam to exhaust to the atmosphere. The outer end of the tube 14 is supported in the casing 6 by means of a packing gland 38 and packing 40 which provides a tight joint between the casing and the tube adjacent the air chamber 16. If any scale or dirt collects at the entrance of the bore 20 around the tapered head 26, or around the pin 24 in the bores 20 and 22, this dirt and scale may be easily removed by inserting an instrument in the socket 32 of the plug 30 to force the pin 24 back into the steam chamber 8 to allow an increased flow of steam through the bores 20 and 22. This increased flow of steam will act to remove the dirt and scale and it will be observed that this cleaning operation may be carried on without discontinuing the operation of the boiler governor.

The variations of the vacuum pressure with the steam pressure of the boiler are made by means of a diaphragm operated valve, the diaphragm of which is in direct contact with steam from the boiler. To this end a second casing 42 is mounted on top of the casing 6 and a valve 52 is mounted in a passageway 44 extending upwardly from the air chamber 16 through the casing 6 and entirely through the casing 42. A passageway 46 formed in the casing 42 is arranged to intersect the passageway 44 at right angles, and a pipe 48 is mounted in the passageway 46 by which the vacuum

pressure formed in the chamber 16 may be imparted to fuel feeding or damper regulating means, or the like, which are to be controlled by the governor. A valve seat 50 is mounted in the passageway 44 directly opposite the lower edge of the passageway 46 and the ball valve 52 is mounted to normally rest on the seat 50. The portion of the passageway 44 extending upwardly from the ball valve 52, is threaded to receive a sleeve 54 which extends downwardly to the upper edge of the passageway 46. A lock nut 55 is mounted on the sleeve 54 by which the sleeve may be locked in any desired position. The lower end of the sleeve 54 forms a valve seat against which the valve 52 may rest if it is moved upwardly from the seat 50. A stem 56 connected with the valve 52 runs through the sleeve 54 and the bore of the sleeve is sufficiently large to provide an air space 58 between the sleeve and the valve stem to permit air to enter into the pipe 48 or into the passageway 44 when the valve 52 is in the proper position for air to enter the pipe or passageway.

The valve 52 is operated through the stem 56 by means of a spring 60 and a steam operated diaphragm 62. The diaphragm 62 is clamped between the casings 6 and 42, the casing 6 having a passageway 64 leading from the steam chamber 8 to a recess 66, covered by the diaphragm. A button 68 rests on the diaphragm 62 and carries a post 70, the free end of which projects into a socket 72 on a lever 74. One end of the lever 74 is connected to the spring 60 and the other end of the lever has a knife edge contact with a bar 76 fixed on the casting 42, see Fig. 3. The diaphragm 62, see Fig. 4, is formed in two layers, the outer layer 63 being fastened to the button 68 by a screw 94, and the inner layer being continuous and in direct contact with the boiler steam. The valve operating stem 56 is connected to the lever 74 intermediate the socket 72 and the spring 60 by means of a universal joint connection. The universal joint comprises a link 78 connected to one end of the stem 56 by a cotter pin 80 and its other end to a pivot pin 82 in the lever 74 by means of a pivot pin 84. Pins 80 and 84 are set at right angles so that the link 78 has a universal joint action to provide for irregularities in the movement of the lever under action of the spring and diaphragm.

With this arrangement the valve 52 may be accurately seated on the valve seats 50 or 54 in any position of the fulcrum lever 74, thus insuring an accurate and positive operation of the valve. If any scale or dirt collects on the valve 52 or the valve seats 50 and 54, the valve stem 56 may be raised and lowered manually to permit the movement of the valve for removing the dirt or scale.

The valve 52 and its operating mechanism

are enclosed in a hood for protection from corrosion and breakage. A portion of the hood consists of an upwardly extending section of the casing 42. To the fixed hood portion of the casing 42 is pivotally connected at 86 a movable hood portion 88. The movable hood 88 has an opening 90 at its lower end whereby air may readily reach the passageway 58 in entering the pipe 48 or passage 44. A latch 92 is pivoted to the casing 42 which is arranged to engage a lug 93 on the front of the hood section 88 to hold the movable hood section in fixed position.

The operation of the boiler governor is substantially as follows: Live steam from the boiler enters the chamber 8 and comes in direct contact with the diaphragm 62. Steam passes through the bore 20 in the tube 14 and by the restricted wire drawing flow of steam between the head 26 and the bore 20 any water in the steam will be vaporized so that substantially nothing but vapor passes through bore 20. If the steam is very wet the high temperature of the tube 14 in contact with the pressure steam will assist in vaporizing any water due to the reduced pressure of the steam on the bore 20 so that substantially no water reaches the enlarged bore 22 of the tube 14. Further, as the steam passes through the small bore 20 it will have a high velocity so that a substantially cylindrical body of steam passes into the bore 22 and there is no tendency for steam or water to condense in the bore 22 and for water and steam to pass through the passages 18 into the air chamber 16. Accordingly, the boiler governor may be used in any position with reference to the boiler without having its operation interfered with by wet steam. The velocity of the steam through the aspirating tube 14 tends to draw in air from the chamber 16 through the passages 18 to create a vacuum in the chamber 16 and passage 44. The pressure of the steam against the diaphragm 62 tends to raise the button 68 and at the same time raise the valve 52 through its connection with a lever to permit the air to be drawn in to the tube 44 and ejected with the steam through the tube 14. If the steam pressure is high enough the valve 52 will be raised a sufficient distance to engage the upper valve seat 54 and thus cut off the air flowing into the passageway 44 at which time a full vacuum pressure will be developed in the chamber 16, passage 44, and pipe 48. As the steam pressure varies to raise and lower the diaphragm 62, the valve 52 will reciprocate between the valve seats 50 and 54 to increase and decrease the vacuum effect on the chamber 16 and pipe 48. This change in the vacuum effect will be imparted to the fuel feeding and air con-

trolling mechanism to control the fire of the boiler. The spring 60 opposes the action of the diaphragm and tends to hold the valve 52 on the valve seat 50. The tension of this spring may be adjusted by the wing nut 96 shown in Fig. 2. The adjustment of the spring 60 and the length of the post 70 of the button 68 can be made such that the valve 52 will rise and fall between the valve seats 50 and 54 to maintain any desired vacuum effect in the pipe 48.

The invention having been thus described, what is claimed as new is:—

1. In a boiler governor, a diaphragm subject to gaseous pressure, an aspirator operated by said gas and having an air inlet, a valve controlling the air inlet to said aspirator, and a lever mechanism connected to said valve, said mechanism comprising an operating connection with said diaphragm and a spring opposing said diaphragm.

2. In a boiler governor, a diaphragm subject to gaseous pressure, an aspirator operated by said gas and having an air inlet, a passage connecting with said inlet, a double-seat valve acting to connect said passage to said inlet or to connect said passage to atmosphere, and an operating connection between said valve and said diaphragm.

3. In a boiler governor, a diaphragm subject to gaseous pressure, an aspirator operated by said gas and having an air inlet, a passage connected to the inlet of said aspirator, a double-seat valve arranged to connect the said passage either to said aspirator or to atmosphere, and operating connections between said valve and said diaphragm, said connections including a universal joint.

4. In a boiler governor, a diaphragm subject to gaseous pressure, an aspirator operated by said gas and having an air inlet, a passage connected to the inlet of said aspirator, a double-seat valve arranged to connect the said passage either to said aspirator or to atmosphere, a tensioned device normally holding said valve to one of its seats, and operating connections between the diaphragm and said device adapted to displace said valve.

5. In a boiler governor, a diaphragm subject to gaseous pressure, an aspirator operated by said gas and having an air inlet, a passage connected to the inlet of said aspirator, a double-seat valve arranged to connect the said passage either to said aspirator or to atmosphere, a tensioned device normally holding said valve to one of its seats, and means movable by the diaphragm for opposing the force exerted by the tensioned device.

6. In a boiler governor, a diaphragm subject to gaseous pressure, an aspirator having a longitudinal bore therein and operated by said gas, means forming an air inlet for said aspirator, a valve controlling said

- air inlet and operated by said diaphragm, and a pin mounted in said bore and having an enlarged head at the inlet end thereof to throttle the passage of gas into the bore.
- 5 7. In a boiler governor, a diaphragm subject to gaseous pressure, an aspirator having a longitudinal bore therein and operated by said gas, means forming an air inlet for said aspirator, a valve controlling said air inlet and operated by said diaphragm, and a pin mounted in said bore and having an enlarged head at the inlet end thereof, and means whereby said pin may be reciprocated in said bore without interrupting the operation of the remaining parts of the boiler governor device.
- 10 8. In a boiler governor, a diaphragm subject to gaseous pressure, an aspirator operated by said pressure, means forming an air inlet to said aspirator, a valve for controlling said inlet, a stem and lever connection between the valve and said diaphragm, and a pivoted hood normally enclosing said connection.
- 15 9. In a boiler governor, an aspirator comprising a steam tube; a pin within said tube and having an enlarged head at the inlet end of the tube, and means whereby the position of said head may be adjusted with respect to the inlet of said tube.
- 20 10. In a boiler governor, an aspirator comprising aligned steam and discharge tubes, a pin within said tubes having an enlarged head at the inlet of said steam tube, and an adjustable plug at the discharge end of said air tube, said pin having a shoulder in contact with said plug.
- 25 11. In a boiler governor, an aspirator comprising aligned steam and discharge tubes, a pin within said tubes having an enlarged head at the inlet of said steam tube, and an adjustable plug at the discharge end of said air tube, said pin extending through said plug and having a shoulder in contact with the inner end of said plug.
- 30 12. In combination, a body having a pressure chamber, a movable member closing an outlet from said chamber, the movements of said member being controlled by the pressure of a gas, a passage in the body opening at both ends to the exterior of the body, an aspirator operable by said gaseous pressure, a vacuum chamber in which the suction of the aspirator is effective, and means under the control of said movable member for establishing communication between said vacuum chamber and said passage. 50
- 35 13. In combination, a body having a pressure chamber, a movable member closing an outlet from said chamber, the movements of said member being controlled by the pressure of a gas, a passage in the body opening at both ends to the exterior of the body, an aspirator operable by said gaseous pressure, a vacuum chamber in which the suction of the aspirator is effective, and means under the control of said movable member for establishing communication between said vacuum chamber and said passage, said means including a stem fitting loosely in one 60 end of said passage.
- 40 14. In combination, a body having a pressure chamber, a movable member closing an outlet from said chamber, the movements of said member being controlled by the pressure of a gas, a passage in the body opening at both ends to the exterior of the body, an aspirator operable by said gaseous pressure, a vacuum chamber in which the suction of the aspirator is effective, and means under the control of said movable member for establishing communication between said vacuum chamber and said passage, said means including a stem fitting loosely in one 65 end of said passage, a lever operable by the diaphragm and a universal connection between said stem and lever. 70
- 45 In testimony whereof I affix my signature.

JAMES P. FISHER.
